HORACE CROSSMAN, OF PROVIDENCE, RHODE ISLAND, ASSIGNOR TO HIMSELF AND ALBERT BRIGGS.

Letters Patent No. 69,188, dated September 24, 1867.

IMPROVEMENT IN SELF-ACTING MULE.

The Schedule referred to in these Letters Patent and making part of the same.

TO ALL WHOM IT MAY CONCERN:

Be it known that I, HORACE CROSSMAN, of the city and county of Providence, in the State of Rhode Island, have invented certain new and useful Improvements in Self-Acting Mules; and I do hereby declare that the following specification, taken in connection with the drawings making a part of the same, is a full, clear, and exact description thereof.

Sheet 1 of the drawings exhibits my improved means of connection between the faller-lock and the relief lever, Figure 1 being a side view, and Figure 2 a front view.

Sheet 2 exhibits my apparatus for giving a slow movement to the delivery-rollers while the carriage is running in, (Figure 3 showing a side view, and Figure 4 a section through the axis of the apparatus, and a front view of the parts with which it is immediately connected.)

Sheet 3 exhibits the means employed by me to give a positive movement to the main cam-shaft, and also exhibits an improvement in the escapement.

Sheet 4 exhibits the improved clutch-coupling employed to maintain the connection between the mechanism for operating the carriage in both directions, and the source of motion.

To understand the improvements in the self-acting mule, which are the subject of this patent, will not require a minute description of all the parts of that complex organism which constitutes the entire machine, but only of such portions as will make, to those skilled in the art, the relation of the improvements to the parts with which they are connected intelligible.

It is well known that a self-acting mule is made up of mechanisms appropriate for the performance of the following principal operations: A stationary frame for holding a series of spools wound with the material which is to be spun; a movable carriage mounted on a track, which carriage carries the spindles; a mechanism for causing the carriage to move away from the stationary frame, and in so doing twist the material which is being delivered from the spools; a mechanism for causing the outward movement of the carriage to be arrested at a determined point; a mechanism for reversing the direction of rotation of the spindle after the required degree of twist in the yarn has been obtained, called the "backing-off motion," and at the same time causing the "faller" to move the threads downward from the end of the spindles to the point where the cop is to be formed; a mechanism for causing the carriage to be run inward, and another for giving a slower movement to the spindles, in the same direction in which they whirl to put in the twist, while the carriage is running in for winding the spun yarn upon the cops; and finally, a mechanism for arresting the movement of the carriage as it comes up to the delivery-rollers, adjusting the yarn so as to be twisted by the spindles, and putting into gear the mechanism for again running out the carriage.

Instances of self-acting mules which comprehend the above-described movements, together with others incidental to the full execution of the work required of them, and not necessary to be referred to, will be found in the machines of this class in common use throughout the country.

My first improvement consists in an improved means of connection between the faller-lock and the relief lever. It is very necessary that the faller should be brought down promptly and without loss of time at the moment that the "backing-off" operation commences, preparatory to the winding of the yarn upon the cop. Heretofore the relief lever, or that lever which operates by its weight to keep the chain taut, which pulls down the faller, has been connected directly with the mechanism which locks the faller fast during the running in of the carriage, and as the position of the faller is being constantly changed to give the proper form to the cop, the length of chain is changing in consequence; that is to say, a length of chain which would be suitable for a certain size of the cop and corresponding position of the faller, will be too long to suit the changing conditions due to the change in the size of the cop, and the excess in the length of such chain or its slack must be taken up before any action is had to draw down the faller. While such slack is being taken up the "backing off" is going on, and is obliged to continue longer than it ought with an appropriate length of chain. By my improvement it will be seen, sheet 1, fig. 1, that the relief lever is connected with the locking mechanism of the faller by an intermediate lever, the effect of which is to cause the faller to be operated at the proper moment, as here-

tofore, but after the faller has been locked, the chain which pulls down the faller to position is no longer subject to change, whatever may be the change in position of the mechanism which locks the faller.

A is the relief lever, carrying a loose friction pulley-wheel, *a*, around which the chain *b*, which operates the faller, passes. The faller-lock is provided with a curved groove, *c*, cut in the side of a curved arm, B, projecting from the axle-shaft C, said groove taking in the end of a stud-pin, *d*, attached to the side of an arm, *e*, upon the intermediate connecting-lever D (fig. 2.) A tongue, E, projecting from the under side of the relief lever A (fig. 1) at all times, except when the faller is locked, bears against a stud-pin, *f*, in the side of the connecting lever, whereby any tendency of the relief lever to be raised as the faller is being drawn down by the chain *b* is prevented. So soon, however, as the faller has descended sufficiently far to allow the lever-arm F to become locked by the stud-pin *g*, and the lever F', to which it is attached, falling far enough to permit the stud-pin *g* to engage with the abrupt face *h* of the catch upon the lever F, the tongue E upon the relief lever A will be released from the control of the stud-pin *f* by the falling of the latter to a lower position, as an incident of the change in the relative position of the stud-pin *g* and catch *h*, whereupon the relief lever will become free and bear with its proper weight only upon the chain *b*.

Another improvement relates to a mechanism for giving a slow movement to the delivery-rollers while the carriage is running in, and thereby, during that time, cause a small quantity of yarn to be given off in excess of the quantity delivered while the carriage is running out. The importance of a means to effect this result will be understood when it is considered that as the carriage is running in, and the yarn being wound upon the cops, if the untwisted yarn be held, as heretofore, fast at one point in the nip of the delivery-rollers, the twist which has been put into the portion which is being wound will run up to the nip of the rollers, and being unable to go farther, will either break the yarn in its effort to extend itself, or certainly render the yarn weak at that point. If, however, a smaller quantity of yarn can be given off contemporaneously with the running in of the carriage, the twist already in the portion spun will run into and twist the portion so given off, and thereby not only prevent the yarn from breaking and preserve its uniformity, but incidentally add to the capacity of the machine.

In sheet 2, figs. 3 and 4, the arrangement which I employ is shown. Upon the front roller G is keyed a toothed wheel, G¹, which in this instance is furnished with thirty-two teeth around its periphery. G² is a similar wheel, with the exception that in this instance it is furnished with thirty-one teeth, and instead of being fast upon the roller G, it is loose upon the same, and is provided with a long hub, *i*, which extends through the side of the hollow pulley *j* which encloses both wheels. Inside this hollow pulley, and geared respectively with the toothed wheels G¹ G², are two pinions H H', or more properly two pinions upon one hub, the portion H, in this instance, having fifteen teeth, and the portion H' having fourteen teeth. The hub of this double pinion is fitted so as to turn freely upon an axle, *k*, passing from side to side of the hollow pulley *j*. Upon the end of the hub of the toothed wheel G², and outside the casing or hollow pulley *j*, is keyed a catch-wheel, I, with the teeth of which a pawl or holding-dog, *l*, may be made to engage. A continuous rotary movement is given to the hollow pulley *j* by means of a belt, *m*, or other means, deriving motion from any convenient source, as the driving-shaft of the mule-head. Now it is quite evident when the carriage is running out and the stretch being made by the spindles; the fast gear-wheel G¹ will give motion to the pinion H', and such pinion being fast to its fellow-pinion H, a movement around its axis will be imparted to the gear-wheel G², it being understood that at this time the catch-wheel I is not blocked by the dog *l*. So soon, however, as the carriage commences to run in, the mechanism, which during the running out of the carriage gives rapid motion to the delivery-rollers, must necessarily be thrown out of gear, (the clutch-box I¹ I² being open as seen.) The slow movement of the rollers in the same direction now commences by the fact that the catch-wheel I, being now held fast by the dog *l*, the rotary movement of the hollow pulley *j* will cause the double pinion H H' to be revolved around its axis whereby a slow rotary movement will be given to the fixed gear-wheel G¹ and the front roller G, and the rapidity of the movement will always be in proportion to the diameters of the wheels G¹ G² relatively to their engaging pinions H H'. In this case, with a stretch of sixty inches when the carriage is running out, there will be a delivery of three inches while the carriage is running in, or a gain in production of five per cent, which, in a mule capable of making three stretches per minute, would in the aggregate effect an important economy.

The means by which the holding-dog *l* is operated is as follows: It is attached to an axle-shaft mounted in bearings in the standard J, which is located at the side of the hollow pulley *j*, and constitutes one of the supports for the front roller. Upon the end of this axle-shaft, opposite to that which carries the dog, is a lever-arm, *k*, one end of which is weighted, and the other is connected by a link-rod, *n*, with the long lever L, which in this, as in other self-acting mules, controls the escapement-wheel upon the cam-shaft. The position of this long lever L will determine the position of the lever-arm *k*, and consequently the engagement of the dog *l* with the catch-wheel I, and its proper position during the running in of the carriage, is such that the dog will during that time be engaged with the teeth of the catch-wheel, and at other times be moved away therefrom.

Another improvement consists in the means for giving a positive movement to the main cam-shaft, and is an improvement upon the means described in the Letters Patent granted to H. S. Bartlett on the 12th day of April, A. D. 1864. It has been found practically impossible to construct toothed gears within the dimensions required, sufficiently strong to withstand the shock to which they are exposed. While on the one hand a positive motion is very desirable, it is important that the means by which it is obtained should possess not only strength, but some degree of elasticity. I have effected this by substituting in place of the toothed gears shown in Bartlett's patent, a chain gear, as exhibited in the drawings, sheet 3; Figures 5 and 6. Thus M is a wheel provided with the projecting points *o* around its periphery, with which the links of the chain M' engage in a way well understood. By the simple change of means for imparting motion to the cam-shaft I am enabled to distribute the shock among the several bearing points of the chain gear instead of having it concentrated

upon any one tooth of a gear, and there is sufficient elasticity to the chain to satisfy the necessities of the case. It will be observed also that I form the face or periphery of the escapement-plate P with four ratchet-teeth corresponding with the four stop-dogs in the side of the plate, each of these teeth having an abrupt face, p, and a long back, q, as shown. In connection with the plate so formed I use a combined spring-brake and stop, Q, which takes the place of the pins and spring-lever on the back of the plate employed heretofore, and greatly simplifies the arrangement.

Another improvement consists in the means for communicating motion to the mechanism which drives the carriage in both directions. It consists of a peculiar friction-clutch, which is essentially a positive connection so long as the resistance to be overcome is not superior to the force which holds the two surfaces of the clutch together, and is not liable to derangement from slight causes, as in the case of the friction-wheels heretofore used to drive the carriage. As will be seen in Figure 8, sheet 4, the teeth of the clutch R are made v form. The faces of the two parts of the clutch are held together by the action of a spring or its equivalent. If any unusual resistance is encountered the springs will yield and allow the teeth on the clutch faces to slip over each other. Unless, however, such unusual resistance occurs, the motion is communicated by it as promptly and as effectually as if the faces of the clutch were so constructed as to be non-yielding.

What I claim as my invention, and desire to secure by Letters Patent, is—

1. Connecting the faller locking mechanism with the relief lever in a self-acting mule by an intermediate lever connection, operating substantially as described for the purposes specified.
2. Imparting a slow movement to the delivery rollers in a self-acting mule during the time that the carriage is running in, by the means substantially as described.
3. The combination and arrangement of the catch-wheel I, holding-dog L, and lever L with the mule-carriage, substantially as described for the purposes specified.
4. Combining the main cam-shaft in a self-acting mule with a chain gear, as arranged and shown, to give motion to the same, substantially as described.
5. The combination of the escapement-plate P, whose periphery is formed with ratchet-teeth, as shown, with a spring-brake and stop, Q, substantially as described.
6. Combining a mule-carriage with its source of motion by means of the peculiar friction-clutch R, substantially as described.

HORACE CROSSMAN.
